UNITED STATES PATENT OFFICE.

WILLIAM FAERBER, OF CHICAGO, ILLINOIS.

APPARATUS FOR SHAMPOOING LADIES' HAIR.

1,028,341.

Specification of Letters Patent.

Patented June 4, 1912.

Application filed March 25, 1912. Serial No. 686,112.

To all whom it may concern:

Be it known that I, WILLIAM FAERBER, a citizen of the United States, and resident of Chicago, in Cook county, State of Illinois, have invented certain new and useful Improvements in Apparatus for Shampooing Ladies' Hair; and I do hereby declare that the following description of my said invention, taken in connection with the accompanying sheet of drawings, forms a full, clear, and exact specification, which will enable others skilled in the art to which said invention appertains to make and use the same.

This invention has general reference to improvements in an apparatus for use in ladies' hair dressing establishments for shampooing and washing ladies hair *in situ*; and it consists, essentially, in the novel and peculiar combination of parts and details of construction, as hereinafter first fully set forth and described, and then pointed out in the claim.

In the drawings already mentioned, in which this invention is fully and clearly illustrated, Figure 1 is a side elevation of the complete apparatus. Fig. 2 is a plan of the same, like parts being designated by the same characters and symbols of reference in both figures.

The object of this invention is the production of an efficient, serviceable and very convenient apparatus which is especially designed for use in ladies' hair dressing establishments for washing and shampooing ladies' hair.

This invention, therefore, includes a portable or movable couch or other similar furniture A, upon which a lady may take a reclining position, said couch being so placed that the lady's head may rest upon a cushion, hereinafter to be particularly described.

B, designates, as a whole, a cabinet which is open at its forward end, said cabinet including a wall-section C, and two wings, or sections D, D^a, hinged to the wall section in any convenient manner. These two wings are framed structures one side of which is provided with a mirror 12, while at the rear thereof there are provided a series of shelves 13, supported in a substantial manner on brackets 14, said shelves being constructed to afford means on which towels, brushes, soap, combs, and other paraphernalia may be placed to be within easy reach of the

operator when performing his or her task of attending to the lady's hair. In front of the wall section C there is located a basin E, said basin having a long, sloping, forward wall 15, on which the lady's hair may be spread when being operated on, said basin having a waste pipe 16, by which water is discharged from said basin. At the upper end of the wall section C there is a forwardly extending canopy F, to which a three-way faucet 17, is attached, there being a hot, and a cold, water pipe, 18, 19, respectively, connected to this faucet, whereby either hot, tempered, or cold water may be drawn from said faucet, as occasion may require. In the forward margin or lip of the basin there is an excision or cut-out 20, and in this cut-out there is affixed a, preferably rubber, cushion which cushion may be of the pneumatic type so as to be absolutely sanitary. Upon this cushion a lady will rest her head so that her tresses may be spread upon the long, sloping, front portion of said basin, where they will be operated on by an attendant, and finally rinsed by water passing from the three-way faucet 17 through a suitable hose 21, and a rose-nozzle or sprinkler 22, connected to said faucet.

During the time that water is being used on the lady's hair the two side wings or hinged sections D, D^a, are so located as to occupy a position at the sides of the basin E^a, which prevents water from being splashed over the floor on which this apparatus is mounted, while when the wings are swung to the position shown in Fig. 2, the shelves at the back of the wings and the articles thereon, are hidden from view.

I prefer to cover the forward surface or face of the wall section C with sheet metal facing 23, the body of said wall section being usually of wood, which will make this apparatus perfectly sanitary; and in order to enhance the appearance thereof, I may employ highly polished and nickel, or silver-plated sheet metal for this facing 23. I may also, if desired, surround the pedestal 24, of the basin E with a sheet metal jacket 25, of the same quality of sheet metal as the facing of the wall section.

An apparatus of the construction described is very complete, compact, and well adapted for the purpose for which it is designed.

Having thus fully described this inven-

tion, I claim as new and desire to secure by Letters Patent of the United States—

An apparatus for the purpose stated, comprising, in combination, a wall-section, side wings hingedly connected to said wall section at the forward margin thereof, a basin located in front of said wall section, said basin having a long, sloping, forward wall, there being in said forward wall

10 at the upper edge thereof, a cut-out, an elastic cushion located in, and occupying the

space of, said cut-out, and a water supply including a three-way faucet and flexible hose, as and for the object stated.

In testimony that I claim the foregoing as 15 my invention, I have hereunto set my hand in the presence of two subscribing witnesses.

WILLIAM FAERBER.
